UNITED STATES PATENT OFFICE

149,338

DESIGN FOR A CANDY SUCKER

Gustave W. Carlson, Superior, Wis.

Application August 5, 1946, Serial No. 132,290

Term of patent 14 years

(Cl. D82—2)

To all whom it may concern:

Be it known that I, Gustave W. Carlson, a citizen of the United States, residing at Superior, in the county of Douglas and State of Wisconsin, have invented a new, original, and ornamental Design for a Candy Sucker, of which the following is a specification, reference being had to the accompanying drawing, forming part thereof.

In the drawing:

Fig. 1 is a front elevational view of a candy sucker showing my new design;

Fig. 2 is a central sectional view on the line 2—2, Fig. 1.

The essential features of my design for a candy sucker reside in the integral unit comprising a disc-like head portion carrying indentures representing eyes, nose, and mouth upon opposite faces thereof and a smaller plain disc-like body

or handle portion encased by a wrapper or the like.

I claim:

The ornamental design for a candy sucker, as shown and described.

GUSTAVE W. CARLSON.
